UNITED STATES PATENT OFFICE.

HENRY W. KIRCHNER, OF ST. LOUIS, MISSOURI.

TRANSPORTATION SYSTEM.

Application filed April 4, 1921. Serial No. 458,471.

My invention relates to improvements in transportation systems in which a carrier, such as a railroad car, barge, truck, or the like, is designed to receive a plurality of 5 freight containers which are adapted to be removably and interchangeably positioned on the platform or body of said carrier, whereby said containers can be readily loaded and moved from one carrier to another. 10 My present invention is particularly designed as an improvement upon the transportation system disclosed in my copending application filed December 15, 1920, Serial No. 430,902, now Patent No. 1,414,516, dated 15 May 2, 1922.

When a container is placed on a carrier, said container will be caused to sway and rock when the carrier is set in motion, the point of fulcrum of this rocking motion being located along the bottom edge of the container. This swaying or rocking motion of the container is caused by the heaving and jarring of the moving carrier or by the momentum when the carrier is rounding a 25 curve or coming to a stop.

The object of my invention is to provide a carrier and unit freight containers which are adapted to be positioned on said carrier and have interengaging relations therewith 30 whereby said containers are locked against any rocking or lateral movement so that said containers will be held firmly in position on the carrier and prevented from being displaced by the heaving and jarring of said carrier.

Other objects of the invention are to provide a unit container adapted to be positioned on a carrier and having portions which are designed to engage portions of 40 said carrier whereby said container can be moved in a vertical direction out of engagement therewith but is locked by virtue of the interlocking engagement of said portions against rocking or swaying movement.

45 A further object is to provide means on said carrier for cooperating with said containers so that the latter are held against movement in a vertical plane, and thereby locked in position on said carrier.

50 With these and other objects in view, my invention consists in certain novel features

of construction and arrangement of parts hereinafter more fully described and claimed, and illustrated in the accompanying drawings, in which—

55

Figure 1 is a plan view of a carrier,—in this instance a railroad car—having a number of containers positioned thereon.

60

Figure 2 is a vertical cross section on line 2—2 of Figure 1.

65

Figure 3 is a perspective detail view of a container looking at its underside.

Figure 4 is a perspective detail view of one of the receptacles designed to be positioned on the carrier to receive portions of 65 the container.

Figure 5 is a perspective detail view of a closure member used to normally close the receptacle.

Figure 6 is a horizontal cross section 70 through the receptacle and a portion of the container showing said container in locked position.

Figure 7 is a plan view of the means used in locking containers on the carrier and 75 showing said means in locked position.

Figure 8 is a similar view showing said means in unlocked position.

Figure 9 is a cross section taken on line 9—9 of Figure 7.

80

Figure 10 is a vertical cross section through the carrier and showing the container locked thereon.

Figure 11 is a vertical section through the carrier showing the container removed and 85 the closure plate locked in its closed position.

Figure 12 is a plan view of a modified form of carrier with some of the containers in position thereon.

Figure 13 is a vertical cross section on line 90 13—13 of Figure 12.

Figure 14 is a perspective detail view of a modified form of a receptacle in position on the carrier.

Referring by numerals to the accompanying drawings which illustrate a practical embodiment of my invention, 10 indicates a carrier, such as a railway car, having a flat body or supporting platform which is provided with a series of diagonally disposed 100 vertical apertures forming receptacles or sockets 11. These receptacles are provided

with horizontal flanges in which are seated suitable fastening devices such as bolts 12, which engage the carrier and hold said receptacles in position therein.

5 The body of each receptacle extends downwardly through the apertures formed in the carrier, and formed in the body of each receptacle is a vertically disposed opening 11^a which is preferably rectangular in cross-section. These receptacles are arranged in series of four, and the series are arranged in two rows which are parallel with the longitudinal axis of the carrier. Projecting outwardly from a side wall of each receptacle 15 are lugs or ears 14, in which are seated the ends of a rod 15 which forms a pivotal support for a closure plate 16. Closure plate 16 is adapted to normally close the upper end of opening 11^a formed in the corresponding receptacle 11 by means of a coiled spring 17 positioned on rod 15 and having one end anchored on said receptacle and its opposite end pressing against the underside of closure plate 16. The vertically disposed 20 opening 16^a formed in one of the side walls of receptacle 11 provides clearance for closure plate 16 when the same is pressed downwardly and outwardly by the insertion of lugs or depending projections 18 formed on 25 the underside of containers 19. These projections are preferably diagonally disposed on the container and are spaced with relation to each other whereby they coincide with and are adapted to enter the openings 30 11^a of corresponding receptacles 11 when container 19 is positioned on carrier 10.

Slidably mounted in one of the side walls of each receptacle 11 and preferably oppositely disposed to the pivotal mounting of closure plate 16 is a locking bolt or pin 20, the inner end of which is adapted to enter a recess 18^a formed in one of the side faces of the projection 18. The outer end of bolt 20 is provided with a vertical pin 21 which 40 traverses an angularly disposed slot 22 formed in the outer end of arm 24, the latter projecting laterally from a bar 25 transversely mounted in bearings 26 on the under side of the carrier 10.

50 There is a series of bars 25, and each bar is provided with a plurality of lateral arms 24 so as to lock simultaneously all four projections on each container. In the drawings, I have shown the bars 25 arranged transversely on the carrier whereby the two containers can be locked simultaneously by the operation of each bar; but if desired, bars 25 can be mounted longitudinally on the carrier for locking one complete row of containers, or a portion thereof, simultaneously by said bar. Bars 25 are operated by manually operable levers 27 fulcrumed on the underside of the carrier and adjacent to each end of said bars 25. By operating the levers 60 27 in the proper direction, bar 25 is caused

by virtue of downwardly depending portions or pins 25^a carried by said bar on each side of said levers 27 to slide forwardly or rearwardly, whereby bolts 20 are caused to move inwardly or outwardly by the angularly disposed horizontal slots 22 engaging vertical pins 21 fixed to the upper ends of each bolt 20.

70 In the modified forms illustrated in Figures 12, 13 and 14, the sides of the carrier 10^a are provided with brackets 28 which project outwardly from said carrier and are provided with angularly disposed pockets or openings 29.

75 By arranging the brackets 28 outwardly on the sides of the carrier, I increase the space between the longitudinal rows of containers so that a person can pass between the rows of containers or I can utilize the space so gained by increasing the size of the containers. I am also enabled to reduce the 80 number of apertures formed in the body of the carrier by use of the brackets.

85 Normally, openings 11^a are closed by closure plates 16, which move upwardly into closing position under the influence of springs 17. The upward movement of plates 16 is limited so that their upper faces are flush with the flanged upper ends of receptacles 11 and the upper or supporting 90 face of the carrier 10, when in closed positions. When in this position plates 16 are locked against downward movement by locking bolts 20 which are moved into extended position so that their inner ends engage the undersides of the corresponding 95 closure plates 16. Thus the plates are held against displacement, so that workmen stepping on said plates will not be injured by the yielding of said plates under the weight 100 of the workmen.

105 To move locking bolts 20 into their locking position, bar 25 is moved in the direction indicated by the arrow in Figure 7 by means of one of the levers 27 so as to bring 110 lateral arms 24 toward receptacles 11. This forward movement of bar 25 causes slots 22 to operate pins 21, whereby bolts 20 are moved inwardly into receptacles 11 and under closure plates 16.

115 In order to place a container in position on the carrier, a corresponding bar 25 is operated by means of lever 27 to move in the direction indicated by the arrow in Figure 8, whereby its lateral arms 24 are moved 120 from receptacles 11 so that locking bolts 20 through their engagement with angularly disposed slots 22 will be retracted or moved outwardly out of engagement with closure plates 16. Container 19 is now placed in 125 position on the carrier so that its legs or downward projections 18 will coincide with openings 11^a formed in receptacles 11. The weight of the container will overcome the 130 strength of springs 17 when projections 18

are inserted in said openings and cause said plates to move into the position shown in Figure 10. In this position the container is resting on the carrier and the depending 6 projections occupy positions with their respective receptacles or sockets.

To lock the containers in position, the corresponding lever 27 is operated to cause bar 25 to slide in bearings 26 and bring arms 24 10 toward receptacles 11. The inclined walls of slots 22 will force pins 21 to move toward receptacles 11 and thereby move the inner ends of bolts 20 into the receptacle 11 so as to enter recesses 18^a formed in the corresponding faces of legs 18, whereby the container is locked against vertical movement.

The receptacles for receiving the legs or projections on the carriers are preferably arranged in groups of four, radially disposed, so that the arc of rocking movement of the legs should the container rock on either side edge, will be such that the different radii will produce a binding effect, tending to prevent accidental displacement of the container.

25 These receptacles are arranged in groups of four for the small unit container and these groups are also preferably arranged in definite relation to each other so that a single unit or a multiple thereof may be located 30 and locked in position on the carrier. This enables the carrier or carriers to be standardized whereby the unit containers or multiples thereof are interchangeable and can be transposed from one position to another 35 irrespective of the nature of the carrier, i. e., the carrier may be a truck, railway car, a barge, or the like. When the containers are on a platform and resting on their legs or projections, a space is provided under them 40 onto which a truck may be introduced, for the purpose of moving them from place to place, or the containers may be moved from place to place by a derrick, crane, or overhead carriers.

45 In Figure 12, I have shown unit containers 19 as being spaced apart on the carrier so as to provide a central passageway therebetween. In Figure 1, these unit containers are shown more closely arranged. At 19^a 50 in Figure 12, I have shown in dotted lines a multiple container which extends entirely across the car so that its legs 18, disposed at its four corners may be received in the pockets 29 at the edges of the carrier. At 55 19^b, Figure 12, I have shown a still larger multiple container which may also be provided with legs 18 at its four corners to engage with the pockets 29 at the edges of the carrier. According to the illustration in 60 Figure 12, the container 19^a has a capacity of about three times that of one of the smaller size containers shown in this figure, whereas the multiple container 19^a has a capacity of about three times that of one of the 65 unit containers and the large container 19^b

has a capacity of about nine times that of one of the unit containers 19.

It will be observed that when the multiple containers 19^a or 19^b are used on the carrier, the intermediate pockets 11^a are not in use 70 and consequently the legs at the four corners of these multiple containers in effect straddle the platform of the carriage; and whether the small units or a multiple of a unit, such as shown in Figure 12, is mounted on the 75 carrier, one or more edges of the container will overhang a side edge of the carrier. This permits the legs which extend downwardly from these overhanging portions to enter the "stake pockets" 29, these legs by 80 their engagement with the "stake pockets" at the side edges of the carrier constituting the fastening means for holding the container against lateral and longitudinal displacement as well as against tilting movement.

85 The pockets 11^a and 29 are so disposed on the carrier that a unit container or a multiple thereof may be interchangeably positioned on the carrier according to the lading and the desire of the shipper.

90 What I claim is:

1. The combination with a carrier, of a container supported on the floor thereof and having projections engaging said carrier, said projections occupying planes relative 95 to said carrier so that when said carrier is tilted and the center of gravity of said container is changed, the arcs of movement from the fulcrum point of said container are such as to bind said container in its 100 seat.

2. The combination of a carrier having a flat supporting surface and means below the level of said surface for engaging a unit container or a multiple thereof at predetermined points, whereby movement of said unit container or its multiple in any direction is prevented.

3. The combination of a carrier and a container having radially disposed intervening parts whereby the movement of the container on the carrier is prevented.

4. The combination of a carrier and a container of a unit size or multiple thereof, said container having projections designed 115 to interengage with said carrier, and means for locking said container on said carrier against tilting movement.

5. The combination with a carrier, of a container of a unit size or multiple thereof, 120 said container adapted to be removably positioned on said carrier and having portions which are arranged to enter into intervening relation with portions of said carrier, whereby said container is held against 125 rocking or swaying movement.

6. The combination with a carrier, of a plurality of containers of a unit size or a multiple thereof adapted to be removably positioned thereon and having portions 130

- which are arranged to interchangeably enter into interengaging relation with portions of said carrier when the same are positioned thereon, whereby each container is movable upwardly in a vertical direction but held against rocking or swaying movement, and means for locking said containers against movement in a vertical direction.
7. The combination with a carrier, of a plurality of containers adapted to be removably positioned thereon, open top receptacles arranged in said carrier and having their upper ends flush with the upper face of said carrier, projections depending from the bottom of each container and adapted to enter said receptacles when the container is positioned on the carrier, whereby said container is locked against lateral or rocking movement, and closure members arranged in each receptacle and adapted to normally close the open tops thereof.
8. The combination with a carrier, of a plurality of containers adapted to be removably positioned thereon, open top receptacles arranged in said carrier and having their upper ends flush with the upper face of said carrier, projections depending from the bottom of each container and adapted to enter said receptacles when the container is positioned on the carrier, whereby said containers are locked against lateral or rocking movement, closure members arranged in each receptacle and adapted to normally close the open tops thereof, and means for locking said closure members in closed positions.
9. The combination with a carrier, of a plurality of open top receptacles fixed therein, unit containers adapted to be removably positioned on said carrier, and a plurality of projections extending downwardly from the bottom of each container and adapted to enter certain of said receptacles when the container is positioned on the carrier and hold said container against lateral or rocking movement.
10. The combination with a carrier, of a plurality of open top receptacles fixed therein, unit containers adapted to be removably positioned on said carrier, a plurality of projections fixedly secured to and extending downwardly from the bottom of each container and adapted to enter certain of said receptacles when the container is positioned on the carrier and hold said container against lateral or rocking movement, and means mounted on said carrier and adapted to engage said projections and lock said containers in position on said carrier.
11. The combination with a carrier, of a plurality of open top receptacles fixed therein and arranged in series in spaced relation with each other, closure members adapted to normally close the open tops of said receptacles, interchangeable unit containers adapted to be removably positioned on said carrier, a plurality of projections extending downwardly from the bottom of each container and adapted to enter a series of said receptacles when the container is positioned on the carrier, said closure plates being adapted to be displaced from their normal position by the insertion of projections on the container.
12. The combination with a carrier, of a plurality of open top receptacles fixed in said carrier, closure members adapted to yieldingly close the open top ends of said receptacles, unit containers adapted to be removably positioned on said carrier, a plurality of projections depending from the body of each container and adapted to displace said closure members and enter said receptacles, and means for locking said closure members in closed position when the container is removed from the carrier.
13. The combination of a carrier, of containers having feet rigidly secured thereto and extending below the level of the carrier, and means rigidly connected to said carrier for receiving said feet to prevent the containers from shifting and tilting on the carrier.
14. The combination of a carrier, a container extending across the carrier and provided with fixedly mounted downwardly extending portions, and means provided at the edges of the carrier for cooperating with said portions to prevent the container from shifting and tilting on the carrier.
15. The combination of a carrier, a container extending across the carrier and having rigid feet which straddle the carrier, and pockets at the outer edges of the carrier for receiving said feet thereby preventing the containers from shifting and tilting on the carrier.
16. The combination of a carrier, a container overhanging the edges of said carrier, and means on said overhanging portions of the container for holding the same in position against shifting and tilting movements.
17. The combination of a carrier having a platform, a container overhanging the edges of said platform, and means located at the edges of the platform for engaging the overhanging portions of a container for holding the latter in position.
18. The combination of a carrier, a container overhanging the edges of said carrier, and means on said overhanging portions for cooperating with complementary means located at the edges of the carrier for holding the container in position.
19. The combination of a carrier, a container adapted to be supported thereby, said container having a dimension greater than the corresponding dimension of the carrier when said container is in position on said

carrier, and fastening means located within the zone of such unequal dimensions for securing the container to the carrier.

20. A carrier having pockets or recesses 5 designed to co-operate with protuberances on a unit container or a multiple thereof.

21. In combination, a carrier having a flat load supporting floor with symmetrically arranged pockets or recesses, and unit and 10 multiple unit containers each having protuberances for insertion in different ones of said pockets.

22. A carrier having pockets or recesses arranged in a series of definitely arranged 15 groups, a unit container having protuberances for engaging the pockets or recesses of a certain group, and a multiple container having protuberances for engaging certain of the pockets or recesses in two or more 20 groups.

23. In a carrier of the character described, a platform, containers disposed thereon and having feet extending below the level of the platform, and means rigidly connected with 25 said platform for receiving said feet to prevent the containers from shifting and tilting on said platform.

24. In a carrier of the character described,

a platform, containers disposed thereon and having feet extending below the level of the 30 platform, and pockets rigidly connected with said platform for receiving said feet to prevent the containers from shifting and tilting on said platform.

25. In a carrier of the character described, 35 a platform, containers disposed thereon, feet on said containers extending below the top of said platform, and means provided at the outer edge of said platform for receiving said feet to prevent the containers from 40 shifting and tilting on said platform.

26. In a carrier of the character described, a platform provided with pockets at its outer edge, containers disposed on said platform, and feet on said containers extending into 45 said pockets to a sufficient depth to prevent the containers from shifting and tilting on said platform.

27. The combination of a carrier, and a container having engageable locking devices 50 beneath its floor and near its medial line, and engaging locking devices on the carrier for cooperation with said devices.

In testimony whereof I hereunto affix my signature this 31st day of March, 1921.

HENRY W. KIRCHNER.
